UNITED STATES PATENT OFFICE.

JOHN ALLEN HEANY, OF FLINT, MICHIGAN, ASSIGNOR, BY MESNE ASSIGNMENTS, TO
A. E. L. LECKIE, OF WASHINGTON, DISTRICT OF COLUMBIA.

ELECTRIC STARTING AND GENERATING MECHANISM FOR VEHICLES.

1,103,672.

Specification of Letters Patent.

Patented July 14, 1914.

Application filed June 7, 1910, Serial No. 565,478. Renewed December 4, 1913. Serial No. 804,764.

To all whom it may concern:

Be it known that I, JOHN ALLEN HEANY, a citizen of the United States, and a resident of Flint, in the county of Genesee and State 5 of Michigan, have invented certain new and useful Improvements in Electric Starting and Generating Mechanism for Vehicles, of which the following is a description.

The invention relates to a device which 10 may be applied to a liquid hydro-carbon or gas engine and may be utilized in connection with said engine for starting the same and for maintaining, after being started, a suitable supply of electrical energy by which it 15 may be actuated and by which the ignition and lighting systems of any desired form may be supplied with current.

The object of the invention is to provide a simple and compact device which may be 20 applied directly to an engine and will provide a means for initially starting said engine as well as a means for storing energy for the ignition circuit of the engine and such other circuits as desired.

25 A further object is to provide a dynamo electric machine for starting an engine and so arranging its various parts that it may be utilized in connection with the "time-shaft" which distributes the current to the 30 various cylinders of the engine.

A still further object is to provide an arrangement by which the various driving and driven shafts will be automatically 35 coupled and uncoupled to give the proper driving relation from the dynamo electric machine to the engine and from the engine to the dynamo electric machine.

Referring to the drawings: Figure 1 is a 40 side elevation of an engine illustrating the application of the dynamo electric machine. Fig. 2 is a front-face view of the engine shown in Fig. 1, the cooling fan and appurtenant parts being removed. Fig. 3 is a side elevation partially in section of the 45 dynamo electric machine as illustrated in Fig. 1. Fig. 4 is a detail view in horizontal section through the casing and appurtenant parts illustrating the main shaft in plan. Fig. 5 is a detail view of a ratchet clutch 50 such as employed. Fig. 6 is a diagrammatic view illustrating the general wiring circuits.

It has heretofore been common practice to employ a magneto geared to the engine shaft in order to provide suitable current 55 for the ignition system of an engine and said

magneto devices have been utilized in conjunction with storage batteries so that the generator might directly act in the ignition circuit or might act to store energy in the storage battery from which the proper current for the ignition circuit might be derived.

It is one of the principal objects of the present invention to provide a compact mechanism so applied to the magneto shaft 60 which is, as ordinarily used, such that by suitable connections, the dynamo electric machine may be utilized in conjunction with a source of electrical supply to start the engine. Said engine when once started will 65 in turn drive the dynamo electric machine as a generator and current derived from such a drive is utilized in the ignition circuit and may be used in lighting or other circuits. As illustrated herein, the armature 70 of the dynamo electric machine is illustrated as geared to the engine shaft which in turn has suitable gearing connections with the timing device by which the current is distributed at proper intervals to the various 75 cylinders of the engine. Such an arrangement is not absolutely essential to the invention but illustrates a very compact and direct means of connecting the various parts in proper driving relation.

80 Referring to the drawings, the numeral 1, denotes an engine of the liquid hydro-carbon type and is shown as of the four-cylinder type which has a main crank shaft 2, and a clutch 3, by which it may be connected to 85 the mechanism to be driven. It is of the automobile type of well-known form and the mechanism hereinafter described is particularly well adapted for use in connection with an engine of this type inasmuch as it 90 permits starting the engine at will and supplying necessary current for ignition and lighting purposes.

At the forward end of the engine there is 95 a casing 4, which contains a train of gears 5, 6, 7, and 8. The gear 6, drives the fan 9, through a suitable connecting belt 10. The gear 7, is upon the cam-shaft 11, which actuates the valve mechanism of the engine. The gear 8, is upon the main shaft 12, of the 100 generating device which shaft, through spiral gears, 13, 14, drives the time-shaft 15, and actuates a suitable timing device mounted thereon and not specifically illustrated in the drawings. Bolted to the frame of the 105 110

engine is a casing 16, which forms a lower casing and support for the parts of the dynamo electric machine 17, and also serves to provide bearings for the main shaft 12, and intermediate driving and driven shafts hereinafter described.

The armature 18, of the dynamo electric machine is arranged in a vertical position within the field-coils and has a downwardly projecting shaft 19, provided with an anti-friction thrust bearing 20, at its lower end. Adjacent to the armature-core is arranged a gear 21, of the spur type, which meshes with a gear 22, also arranged on a vertical axis upon a shaft 23, and provided with a thrust-bearing 24, both of the gears 21, and 22, have arranged adjacent to them anti-friction bearings 25, 26, which are located in a section 27, of the casing 16.

20 The shaft 19, has adjacent to its lower end a worm-gear 28, which meshes with a worm-gear 29, secured to the main shaft 12, in such ratio that rotation of the armature will rotate the shaft 12, at comparatively slow speed and will, through the train of gearing 5, 6, 7, 8, turn the main shaft of the engine for the purposes of starting it.

Between the gear 22, and its shaft 23, is arranged a roller-clutch 22^a, of the ratchet type such as illustrated in Fig. 5 and with its teeth so arranged that it will slip with reference to the shaft 23, and will communicate no motion when the gear 21 is rotating and the shaft 19 is driving the engine shaft 2 through the main shaft 12 and gears 8, 7, 6, 5. The shaft 23, is provided with a spiral gear 30, which meshes with a coöperating spiral gear 31, arranged upon the section 32, of the shaft 12.

40 Appurtenant to the gear 29, there is a similar clutch 33, arranged in the hub of said gear as illustrated in general view in Figs. 3 and 4. The teeth of this ratchet clutch are so disposed that as the armature rotates in one direction under the impulse of current supply thereto and is operating as a motor, the clutch 33, will bind the gear 29, to its shaft and thereupon the shaft 12 and train of gearing 5, 6, 7, and 8, will turn the engine-shaft 2. As soon as the engine has been started in this manner and speeds up, the clutch 33, will become inoperative permitting the shaft 12, to run away from the gear 29. As soon as the shaft is thus speeded up, the clutch 22^a, will become effective and, thereupon the shaft 12, will, through the spiral gears 31, 30, and spur-gears 22, 21, drive the armature-shaft 19, so that the dynamo electric machine will be operated as a generator and will generate current for storing electrical energy and providing circuits used in conjunction with the engine.

It will be noted that with the worm-gear drive through the gears 28, 29, and the train 65 of gears 5, 6, 7, and 8, a great advantage of

leverage is secured from the dynamo electric machine operating as a motor to the engine shaft. With the spiral gears 30, 31, and spur gears 22, 21, it is apparent that the armature shaft will be driven at comparatively high-speed when the dynamo electric machine is operating as a generator and is being driven from the engine shaft. In either case it is apparent that whether the dynamo electric machine is acting as a motor to drive the engine shaft or acting as a generator being driven by the engine shaft, the shaft 12, will drive the spiral gears 13, 14, and maintain action upon the timing device or distributing device, so that the ignition circuit will be properly timed for the several cylinders. In order to reduce friction an anti-friction thrustbearing 34, is provided at the end of the shaft 12, to take up the thrust of the spiral gears and an anti-friction thrust bearing 35, is provided at the lower end of the shaft 15.

In order to clearly show the operation of the mechanism the several elements are diagrammed as illustrated in Fig. 6, wherein the several parts already referred to are already designated by corresponding reference characters. In this diagram B, indicates the storage battery or accumulator having terminal leads 50, 51, which are connected respectively through switches 52, 53, with a lighting circuit 54, 55, and a main circuit 56, 57, which is electrically connected with the dynamo electric machine 17, and is also connected with the ignition circuit as hereinafter defined. One leg of the circuit 57, is grounded at the common ground G, which may be the motor casing and the leg 56, leads through the conductor 58, to the movable contact 59, of a make and break device. The stationary contact 60, thereof is connected through a lead 61, with a primary coil *a*, of an induction coil grounded as at G, while the secondary coil *a'*, through a lead 62, is connected with a movable or rotary member 63, of the distributing device C. The stationary contacts 64, 65, 66, and 67, through leads 68, 69, 70, 71, are connected with the insulated terminals of the spark-plugs 72, 73, 74, and 75, of the several cylinders of the engine. It is understood that the coöperating contact of these spark plugs is grounded to the common ground and the plugs are not shown herein in detail as they are well-known in the art. Obviously, the switches 52, 53, may be located within ready reach of the operator so that as the switch 53, is closed, the electrical supply B, is connected to the dynamo electric machine 17, to drive said machine as a motor. Thereupon, through the gearing heretofore described, the engine-shaft will be turned and the initial impulse will be given to the main shaft of the engine inasmuch as the timing or distributing device will be actuated and the 130

ignition circuit is cut in and as soon as the engine has attained a nominal speed, the dynamo electric machine will act as a generator and current will then be produced 5 for re-charging the battery B and furnishing energy for the ignition circuit as well as the lighting circuit.

Obviously, the details of the mechanism might be varied to a considerable extent 10 without departing from the spirit or intent of the invention and various forms of gearing might be utilized in place of the specific worm and spiral gear arrangement herein described and shown. It is preferred to use 15 a differentially wound motor so that it is possible to maintain a proper current condition when the dynamo electric machine is operating as a generator and which will operate properly as a motor when under the influence of the current from the battery B. Various switches might be interposed in the 20 circuits for controlling them in any desired relation one with the other, a simple arrangement being herein shown in diagram.

25 What I claim as my invention and desire to secure by Letters Patent is:—

1. A starting and generating mechanism for vehicles embodying a dynamo electric machine adapted for gear connection with an 30 engine shaft and having a casing, a main shaft mounted in said casing, a driving shaft intermediate the armature of the dynamo electric machine and the main shaft and having worm gear connections there- 35 with for driving the latter, and a shaft having spiral gear connections with the main shaft and operatively arranged to drive the armature.

2. In a device of the character described, 40 a dynamo electric machine having a casing, a main shaft extending therethrough, an armature shaft operatively supported transversely to said main shaft, a worm and worm-gear connecting said shafts, a counter- 45 shaft intermediate the main shaft and armature, spiral and spur gears connecting said shafts, and clutch devices intermediate the armature shaft, main shaft and counter-shaft.

3. In a device of the character specified, 50 a dynamo electric machine having its armature arranged on a vertical axis, a main shaft operatively supported with reference thereto, and having gear connections with an engine shaft, worm and worm-gear connections 55 between the armature shaft and main shaft for driving the latter, and connections intermediate the main shaft and armature shaft including spiral and spur gears for driving the armature from the 60 main shaft and clutch devices operatively arranged with reference to the several gears whereby one set of gears will be operative for driving the main shaft and the other set of gears will be operative for driving the 65 armature.

4. In a device of the character described, 70 a dynamo electric machine, a main shaft operatively arranged to be gear-connected with an engine shaft, said main shaft being 75 geared to a timing shaft of the engine, worm-gear connections between the armature shaft and main shaft, a counter-shaft, spiral gear connections between the counter-shaft and main shaft, spur-gears connecting said 80 counter-shaft and the armature shaft and automatic means appurtenant to the gear trains whereby the main shaft will be driven by the armature and the armature will be driven by the main shaft.

5. In a device of the character described, 85 a dynamo electric machine adapted to drive and be driven from a main shaft, a main shaft operatively arranged with reference thereto, and adapted for gear connection with an engine shaft, concentric members operatively connected with the armature and main shaft, gearing interposed between the concentric members, main shaft and armature whereby said armature will drive the 90 main shaft or be driven thereby, and clutch devices interposed in the gearing connec- tions.

JOHN ALLEN HEANY.
